UNITED STATES PATENT OFFICE.

ANTON LÜNEBURG, OF NIESKY, GERMANY, ASSIGNOR TO CHRISTOPH & UNMACK
ACTIEN-GESELLSCHAFT, OF NIESKY, GERMANY.

SLEEPING CAR WITH A SIDE PASSAGE OR CORRIDOR.

Application filed September 27, 1927, Serial No. 222,256, and in Germany December 4, 1926.

This invention relates to a sleeping car with a side passage or corridor, from which access is gained to double compartments each containing four day seats. Its object 5 is to arrange, in addition to the day seats to be converted into sleeping places, upper beds in such a manner that each one is closed separately, so that for each passenger there is available a closed berth or a berth that 10 can be closed. The arrangement is at the same time made in such a manner as to utilize the car to the fullest possible extent.

For the solution of the problem according to the invention is essential the arrangement between the two day seats of a double compartment of one or more completely independent rooms each having separate access from the corridor and from the day compartments.

20 It has already been proposed to arrange within each single compartment of the first-class a smaller compartment, which is accessible from the corridor in the same manner as the first-class compartment but which 25 is, on the other hand, completely closed with respect to the said first-class compartment. This arrangement not only represents a considerable reduction of the volume of the main or first-class compartment but also an 30 unfavorable formation of the interior of these compartments. The additional compartments moreover are very small. The known arrangement is not able to solve the problem contemplated by this invention. 35 The room or rooms, which according to the invention shall be arranged between the day seats of each two double compartments may be arranged in a different manner.

Firstly, the arrangement may be in the 40 form of a separate anteroom which represents, so to say, an access shaft to the upper berths and extends accordingly from the floor to the roof of the car. This anteroom can be completely shut off from the sleeping berths situated below. On the other 45 hand, the upper berths must be again shut off from the anteroom so that the condition mentioned in the beginning is fulfilled.

The anteroom can adjoin the corridor, 50 and the upper berths extend then in the longitudinal direction along the corridor. The lower berths are accessible from the corridor in the usual manner. Such an access is preferably also provided direct to the anteroom from the corridor, in order to allow

the passengers using the upper berths, to get, in an emergency, into the corridor, without having to pass through the lower berths.

The anteroom could be further arranged at the outside wall of the car which is away 60 from the corridor. It is then preferably arranged symmetrically of the transverse partition of a double compartment and accessible only through the single compartments.

While in the former case two upper sleeping berths branch off from the anteroom, in the latter case is provided only one upper berth which is situated above the partition of the lower sleeping berths and projects 70 over the corridor. The upper sleeping berth would be reached accordingly from one of the lower compartments through the anteroom. Also, in this case, it is possible to provide a direct communication between the 75 upper sleeping berth and the corridor, by providing, for instance, in the lateral wall of the upper sleeping berth, which is situated above the corridor, an opening that can be closed and from which can be manipulated an emergency ladder or the like leading to the corridor.

The system of the anteroom could be further arranged in a particularly suitable manner in order to form double compartments 85 in which altogether six day seats, and accordingly six sleeping berths are again arranged in such a manner that the sleeping berths are shut off from each other.

To that end, according to the invention, 90 between the single compartments of two day seats each, is interposed a further compartment with two day seats, which is accessible from the first mentioned compartments and the seats of which are arranged in the longitudinal direction of the car. Between the 95 rear wall of this compartment and the inside wall of the corridor, are arranged side by side three anterooms which are accessible from the corridor and are shut off from the lower compartments. From these anterooms, access can be gained to each of the upper berths which are arranged directly above, and in the same way as the lower berths.

On the other hand the room (or rooms) 100 between the day seats of two double compartments may be in the form of two completely independent sleeping berths each having separate access from the corridor and from

the day compartments, the beds of which are arranged above each other in the same way as cabin berths, while the washing and dressing room has full height. To the berths themselves is therefore allotted half the height of this room. It is a matter, therefore, of arranging one bed only at a relatively small height, and the low height above the bed is not a drawback as the passenger has available the full height of the room for washing and dressing.

The different constructions according to the invention are illustrated by way of example in the accompanying drawing in which

Figures 1 and 2 each show one possible arrangement of a single anteroom, in plan;

Figure 3 shows a third possible arrangement with several anterooms in plan;

Figure 4 is a corresponding cross-section in the direction of the line I—I of Figure 3;

Figure 5 is a longitudinal section through a double compartment in the direction of line II—II of Figure 3;

Figure 6 shows part of the car in plan illustrating the two superposed berths according to a fourth possible arrangement of the rooms as proposed by the invention;

Figure 7 is a corresponding cross-section in the direction of line III—III of Figure 6;

Figure 8 is a corresponding longitudinal section taken in the direction of line IV—IV of Figure 6 looking in the direction of the arrows.

The lower berths are indicated in Figures 1 and 2 by full lines, and the upper ones by dotted lines.

In Figures 1 and 2, *a* is the side passage or corridor from which access can be gained to each of the double compartments *b* which are each provided with a day seat *c* intended for two persons. In each double compartment is provided a transverse partition *d*. Symmetrically of the said partition, in the construction of Figure 1, the corridor *a* is adjoined, according to the invention, by an anteroom *e* for each double compartment, which anteroom in its turn is accessible from each of the compartments *b* through doors *f*. A third door *g* leads as an emergency door from the anteroom into the corridor *a*. This anteroom forms a vertical shaft traversing the inner space of the car. From this space the upper berths *h* are accessible through openings which can be closed. If desired, the anteroom could also be utilized for dressing and undressing. The upper sleeping berths are reached in the well-known manner by ladders or the like.

In the case of Figure 2, the anteroom *e* is situated at the outside wall which is away from the corridor *a*. It is therefore no longer directly accessible from the corri-

dor. In such a case, to each double compartment is allotted only one upper berth *h* extending in the transverse direction, which is thus situated above the partition *d* and extends over the corridor. This latter convenience can be utilized in order to get from the upper sleeping berth direct into the corridor in case of an emergency.

Accordingly, in the latter case only three sleeping berths are provided for four day seats. Nevertheless the utilization of the car in the latter case is still more thorough than in the former. As shown in the constructions illustrated, the first car has 14 day seats and 14 sleeping berths, the latter, of approximately the same length, 15 sleeping berths and 20 day seats.

In the case of Figures 3-5, the two double compartments *b* are separated and between them is arranged a third compartment *b'* which is also provided with two day seats *c'* and is accessible through two doors *i* from the compartments *b*. The compartments *b* themselves adjoin in the usual manner the corridor *a*.

Behind the rear wall *j* of the compartment *b'* are provided three anterooms *e*¹, *e*², *e*³ which are separated from each other by partitions *k*, the two outer anterooms being accessible through doors *f* from the compartments *b*. Moreover, one access each *g*¹, *g*², *g*³ is provided to the corridor *a*. For the middle anteroom *e*², this access is the only one.

These anterooms are also made in the form of a shaft and are intended for reaching the upper berths *h*¹, *h*², *h*³ situated in the same position above the lower berths *c* and *c'*, with the assistance of ladders or the like. One of the persons using the day seats *c* passes, therefore, through the doors *f* into the anteroom *e*¹ or *e*³ and climbs from there to the upper berth *h*¹ or *h*³. The passenger occupying the day seat *c'* as second person, gets to his night berth through the anteroom *e*². The doors *g*¹ and *g*³ form emergency doors for the upper berths *h*¹ and *h*³. Also in this case all the rooms are accordingly shut off from each other or can be shut off, and there are as many sleeping berths as day seats, and at the same time the sleeping car is utilized to the fullest possible extent. While, at present, in a standard sleeping car with four double compartments, there are only 20 sleeping berths for the second class, or ten sleeping berths for the first class, and two second class passengers must always sleep together in one compartment, in a car according to Figures 3-5, twenty four second class passengers can be carried on day seats, for whom are provided also twenty four completely separate sleeping berths. If the car is used entirely as a first class car, there will be available 12 seats and as many sleeping berths.

As indicated in Figures 4 and 5, the upper sleeping berths could be shut off, for instance, by means of rolling shutters *l* which could be locked from the inside in any desired suitable manner.

With the arrangement shown in Figures 6—8 two bedrooms *m*, *n* are provided between the day-seats or lower berths *c* of the double compartments *b*. Room *m* is accessible through door *f* from the left-hand compartment and also through door *g* from the side corridor. The access from the corridor *a* to room *n* is effected through the door *o*, while room *n* is accessible from the right-hand compartment *b* through door *f*. The bedrooms *m* and *n* are shut off from each other and are each provided with a bed *m*¹ and *n*¹, respectively, and also with a wash-stand *p*, *q*. The intermediate wall *r* between the two bedrooms *m* and *n* is arranged so as to have a Z shaped cross-section as shown in Fig. 7. The bed *m*¹ is situated above the bed *n*¹ and both beds are arranged in the longitudinal direction of the car while the berths in the compartments *b* are formed by the day seats arranged in the transverse direction of the car in the known manner.

The berth *m*¹ projects, so to say, into the room *n* and is a little above the floor of this room. As will be seen more particularly from Figure 7 the passenger has available for dressing and undressing or washing a space, which has the full height of the car, while only the space above each of the beds *m*¹ and *n*¹ has half the height of the car.

In so far as each compartment *b* is used only by one passenger the invention makes it possible to use the compartments *b* exclusively as day compartments and to place the rooms *m* and *n* at the disposal of the passengers as sleeping berths. In the compartments *b* themselves washstands *s* are provided in the known manner, which are situated within the walls *t* shutting off the bedrooms *m* and *n* from the compartments *b*.

I claim:

1. In a sleeping car, a corridor arranged at one side of the car, a plurality of double compartments each accessible from the corridor, a room between the day seats of each of said compartments, the said room being separated from the said compartments and said corridor, and a separate access to the said room from the said compartments.
2. In a sleeping car according to claim 1, an upper berth for said room, and the latter being in the form of a shaft, only providing access to the said upper berth and adapted to be shut off from the said compartments.
3. In a sleeping car according to claim 1, two upper berths to which access is had from said room extending in the longitudinal direction along the corridor, the said room being situated between said berths and adjoining the corridor.

4. In a sleeping car according to claim 1, two upper berths to which access is had from said room extending in the longitudinal direction along the corridor and partly extending over the day seats of the said compartments, the said room being situated between said berths and adjoining the corridor.

5. In a sleeping car according to claim 1, an upper berth communicating with said room, and the latter being in the shape of a shaft only adapted to provide access to the said upper berth and accessible through the said compartments.

6. In a sleeping car, a corridor arranged at one side, a plurality of compartments each accessible from the corridor, a further compartment between each two of the first-named compartments only accessible from the adjoining compartment, the day seat of said further compartment being arranged in the longitudinal direction of the car.

7. In a sleeping car, a corridor arranged at one side, a plurality of first compartments each accessible from the corridor, a second compartment arranged between each two of said first compartments, in each of said second compartments two day seats arranged in the longitudinal direction of the car, a small room between the rear wall of each second compartment and the corridor, and an upper berth accessible through said room, the said upper berth being shut off from the interior of the said compartments and the said room being accessible from said corridor.

8. In a sleeping car according to claim 7, wherein the said upper berth is arranged above the day seat of the said second compartment and in the same direction as the day seat.

9. In a sleeping car, a corridor arranged at one side, a plurality of first compartments each accessible from the corridor, a second compartment arranged between each two of said first compartments, in each of said second compartments two day seats arranged in the longitudinal direction of the car, a plurality of upper berths arranged above the day seats of the said first and second compartments and in the same direction as the day seats, and a room between the rear wall of each second compartment and said corridor, the said upper berths being shut off from the interior of the said compartments and accessible through said room and the said room being accessible from said corridor and the adjoining first compartments.

10. In a sleeping car, a corridor arranged at one side, a plurality of first compartments each accessible from the corridor, a second compartment arranged between each two of said first compartments, in each of said second compartments two day seats arranged in the longitudinal direction of the car, an upper berth arranged above the day seat of each second compartment and in the same

direction as the day seat, the said berths being adapted to be shut off from the interior of said compartments, three rooms arranged side by side between the rear wall of said 5 second compartment and said corridor, each said room providing access to one of said berths, the middle room being accessible

from said corridor, and the other rooms being each accessible from one of said first compartments and said corridor.

In testimony whereof I have hereunto affixed my signature.

ANTON LÜNEBURG.
